UNITED STATES PATENT OFFICE

139,594

DESIGN FOR A DOLL OR SIMILAR ARTICLE

Rose Albert Gudt, New York, N. Y.

Application February 11, 1944, Serial No. 112,535

Term of patent 3½ years

(Cl. D34—4)

To all whom it may concern:

Be it known that I, Rose Albert Gudt, a citizen of the United States, residing at Manhattan, in the city, county, and State of New York, have invented a new, original, and ornamental Design for a Doll or Similar Article, of which the following is a specification, reference being had to the accompanying drawing, forming part thereof.

The essential characterizing feature of the design is shown in full lines in the drawing.

I claim:

The ornamental design for a doll or similar article, substantially as shown and described.

ROSE ALBERT GUDT.
